UNITED STATES PATENT OFFICE.

WILLIAM K. BASSFORD, OF METUCHEN, NEW JERSEY.

SAFETY DEVICE FOR OIL HEATERS AND LAMPS.

Application filed October 15, 1921. Serial No. 507,869.

To all whom it may concern:

Be it known that I, WILLIAM K. BASSFORD, a citizen of the United States, and a resident of Metuchen, in the county of Middlesex and State of New Jersey, have invented new and useful Improvements in Safety Devices for Oil Heaters and Lamps, of which the following is a specification.

This invention relates in general to safety devices for liquid fuel heaters and lamps and more particularly to devices of the character described in United States Patent No. 1,343,217 dated June 15, 1920, which will immediately extinguish the flame of a heater or lamp in case the same is tipped over, or becomes overheated so as to prevent the fuel reservoir from catching fire or exploding.

The objects of the invention are to provide a device of the character described embodying novel features of construction whereby a substantially air tight chamber will be formed about the flame of a heater or lamp to immediately extinguish the flame when the heater or lamp is tipped over, or 25 the heat produced by the same reaches a predetermined degree; to provide a device of this character including an extinguishing member normally held in inoperative position by a plurality of weights loosely mounted thereon in brackets or pockets which are formed of fusible metal, or are secured to the said member by fusible fastening means such as rivets or solder, whereby the said weights will be knocked out of said pockets 30 when the heater is tipped over and said fusible pockets or their fastening means will be melted to disconnect the pockets from the said extinguishing member to allow the weights to drop therefrom when 35 the heater becomes overheated so as to release the extinguishing member into operative position to extinguish the flame; to provide novel brackets or pockets to support said weights on the extinguishing member, 40 and to obtain other results and advantages as may be brought out in the following description.

Referring to the accompanying drawings, in which like numerals of reference indicate 50 the same parts throughout the several views,

Figure 1 is a vertical sectional view through the lower portion of a conventional oil heater showing one embodiment of the invention applied thereto;

55 Figure 2 is a horizontal sectional view taken on the line 2—2 of Fig. 1;

Figure 3 is an enlarged transverse sectional view through one side of the extinguishing ring and one of the weight supporting brackets taken on the line 3—3 of Fig. 2;

Figure 4 is a detached front elevation of one of the brackets;

Figure 5 is a fragmentary longitudinal sectional view through one end of one of the pockets taken on the line 5—5 of Fig. 2;

Figure 6 is a detached front elevation of a modified form of pocket;

Figure 7 is a transverse sectional view taken on the line 7—7 of Fig. 6;

Figure 8 is a view similar to Fig. 6, showing a further modified construction of pocket;

Figure 9 is a view similar to Fig. 5 of the pocket illustrated in Fig. 8;

Figure 10 is a top plan view of a further modified form of a weight supporting bracket, and

Figure 11 is a side elevation of the bracket shown in Fig. 10 showing a weight mounted thereon.

For the purpose of illustration, I have shown the invention in connection with a conventional oil heater comprising a base A which removably receives and supports the oil reservoir B. A vertically disposed annular wick tube C is carried by the oil reservoir B and receives an annular wick D which projects downwardly into the reservoir B into the oil, conventional wick adjusting means being indicated at E. A hollow air and flame spreading member F is fitted loosely within the center of the annular wick tube so as to allow air to pass upwardly into the burner to produce proper combustion, said member F being provided with a flame spreading flange G which surrounds the member F and lies over the top of the wick D, a series of air holes H being arranged between this flange G and a similar flange I arranged above the flange G to further spread the flame and enhance combustion. A casing K is mounted upon the base A and encloses the burner in the usual manner. The construction of the oil heater is conventional and no claim is laid to it.

The invention comprises a flame extinguishing ring or snuffer 1 which fits loosely around the exterior of the wick tube C above the top of the oil reservoir B, and is adapted to slide longitudinally of the wick tube.

The top of the extinguishing ring 1 is normally just below the top edge of the wick top so as not to interfere with the flame, and is normally held in this position by a plurality of preferably circular weights 2 loosely mounted in pockets or brackets 3 secured radially upon the exterior of the extinguishing ring, as shown in Figures 1 and 2. The weights are identical in size, so as to 5 balance on the ring 1, and their combined weight is just sufficient to hold the extinguishing ring 1 below the top edge of the wick tube against the action of a light coil spring 4, which is interposed between the 10 ring 1 and the top of the oil reservoir B. It will thus be obvious that if the weights 2 are removed or knocked from the pockets or brackets 3 as by tipping over the oil 15 heater, the spring 4 will immediately force the extinguishing ring upwardly. The upward movement of the ring 1 is stopped by a cap ring 5 which is secured to and surrounds the member F of the burner above the flame spreading flange I, the said cap ring 5 being formed in two semicircular sections 5a having upturned ends 6 which are 20 connected by bolts 7 so that the cap ring can be quickly and easily applied to the member E. The width of the extinguishing 25 ring 1 is such that when it engages the cap ring 5 the extinguishing ring bridges and covers the space between the top of the wick tube C and the cap ring 5, the stop ring 5 serving as a cap for the top of the extinguishing ring. It will thus be seen that a 30 substantially air tight chamber is formed above the wick between the extinguishing ring 1 and the member E so that there is insufficient air for combustion, and the extinguishing ring 1 will be positively held 35 against the cap ring 5 by the spring 4 so as to maintain the closed chamber until all flame is extinguished. The flame is thus quickly extinguished, and if the heater has 40 been tipped over or dropped there is no danger of the oil in the reservoir catching fire or exploding.

In Figures 1-5 inclusive I have shown one 45 form of pocket for supporting the weights 2, which consists of a strip of sheet metal having the ends 8 thereof adapted to be secured to the extinguishing ring and the intermediate portion thereof bent outwardly at substantially right angles at both ends as 50 indicated at 9 to form an offset portion which provides a space between the extinguishing ring and the pocket to loosely receive the weight 2 as shown in Figures 2 and 3. The lower edges of the outwardly 55 bent portions 9 are crimped or bent inwardly as at 10 to form shoulders for supporting the weight 2 and preventing the same from falling through the pocket. In this connection it will be observed that the 60 weights are provided with beveled edges 65

which engage the shoulders 10 so that there will be no tendency of the edges of the weight to jam on the shoulders 10 which would restrain the weights from falling out of the pockets when the heater was jarred or tipped over. The invention contemplates forming the pockets of fusible metal which will melt at a predetermined temperature, or forming the pockets of an infusible metal and securing the same to the extinguishing 70 ring by means of fusible rivets 11 or fusible solder. When the pockets are formed of fusible metal, the metal itself may be fused in spots at the ends of the pockets to secure the pocket to the extinguishing ring. 80

Figures 6 and 7 illustrate a modified form of pocket 12 which comprises a strip of sheet metal having its ends bent at substantially right angles as at 13 and an inturned tongue 14 substantially centrally of the body portion of the pocket which serves to support a weight 2 and prevent the same from falling through the pocket. As above described the pocket may be formed of fusible metal, or the edge of the end portions 13 may be soldered to the ring, as shown in Figure 7. The lower portion of the ends 13 are cut away at 120, and the tongue 14 is of a length to engage the outer beveled side of a weight so that when the heater reaches a predetermined temperature and the solder or the pocket begins to melt, the beveled side of the weight as the weight falls tends to push the pocket outwardly from the extinguishing member, the cut away portion 120 deflecting the pocket away from the spring 4 to prevent entangling of the pocket in the spring. 90

A further modified form of pocket is shown in Figures 8 and 9 similar to the construction shown in Figures 4 and 5 except that the lower edge of the outwardly bent portions 15 are slotted, as at 16, and tongues 17 between the slits bent inwardly to support a weight 2. 100

Figures 10 and 11 show a bracket for supporting a weight 2 comprising a base 18 adapted to be secured to the extinguishing ring 1 and formed with an outwardly projecting and upwardly extending hook 19 which is adapted to support a weight. The weight for use in connection with this form of bracket would be formed with an opening 20 in the edge thereof which would loosely fit over the end of the hook 19, as shown in Figure 11. 110

With this construction it will be observed that the loose mounting of the weights in the pockets or brackets ensures the weights falling out of the pockets when the heater is tipped over, thereby allowing the spring 4 to actuate the extinguishing ring upwardly against the cap ring 5 to extinguish the flame. When the heater becomes overheated the fusible pockets or their fusible fastening means securing them to the extinguishing 120 125 130

ring, will be melted, thereby allowing the weights to drop from the extinguishing ring and permitting the spring to actuate the extinguishing ring to extinguish the flame.

5 While I have shown four weights and four pockets or brackets, it will be understood that more or less weights and brackets may be utilized as may be found desirable, and while several forms of brackets and pockets 10 have been shown and described, it will be understood that this is only for the purpose of illustrating the principles of the invention. Therefore, I do not desire to be limited in the detail construction of the invention 15 except as required by the following claims when construed in the light of the prior art.

Having thus described the invention, what I claim is:

1. The combination with a liquid fuel 20 heater or lamp, of an extinguishing member, means for actuating said extinguishing member to extinguish the flame of the heater, means for holding said extinguishing member normally in inoperative position against 25 the action of said actuating means, and means including a fusible element for connecting said holding means to the extinguishing member so that when the heater reaches a predetermined temperature said fusible element 30 will melt and release said extinguishing member from said holding means to permit said actuating means to move said extinguishing member to extinguish the flame.

2. The combination with a liquid fuel 35 heater or lamp of an extinguishing member, means for actuating said extinguishing member to extinguish the flame of the heater, a weight for holding said extinguishing member normally in inoperative position 40 against the action of said actuating means, and means including a fusible element for mounting said weight on the extinguishing member so that when the heater reaches a predetermined temperature said fusible element 45 will melt and release said weight from the extinguishing member to permit said actuating means to move said extinguishing member to extinguish the flame.

3. The combination with a liquid fuel 50 heater or lamp of an extinguishing member, means for actuating said extinguishing member to extinguish the flame of the heater, a weight for holding said extinguishing member normally in inoperative position 55 against the action of said actuating means, and a support for said weight secured to said extinguishing member by fusible fastening means.

4. The combination with a liquid fuel 60 heater or lamp of an extinguishing member, means for actuating said extinguishing member to extinguish the flame of the heater, a weight for holding said extinguishing member normally in inoperative position against 65 the action of said actuating means, and a

fusible support for said weight secured to said extinguishing member.

5. The combination with a liquid fuel 70 heater or lamp of an extinguishing member, means for actuating said extinguishing member to extinguish the flame of the heater, a weight for holding said extinguishing member normally in inoperative position against the action of said actuating means, and a support secured to said extinguishing member by fusible fastening means to loosely receive said weight so that the weight is displaced from said support when the heater is tipped over and the support is disconnected 75 from said extinguishing member to release 80 said weight when said fusible fastening means is melted.

6. The combination with a liquid fuel 85 heater or lamp of an extinguishing member, means for actuating said extinguishing member to extinguish the flame of the heater, a weight for holding said extinguishing member normally in inoperative position against the action of said actuating means, and a fusible support secured to said extinguishing 90 member to loosely receive said weight so that said weight is displaced from said support when the heater is upset or when said support is melted by a predetermined degree of heat in the heater.

7. The combination with a liquid fuel 95 heater or lamp, of an extinguishing member, means for actuating said extinguishing member to extinguish the flame of the heater, a weight for holding said extinguishing member normally in inoperative position against the action of said actuating means, and a fusible support secured to said extinguishing member to receive said weight, said support permitting said weight to fall from the 100 extinguishing member when said support is melted by a predetermined temperature in the heater.

8. The combination with a liquid fuel 105 heater or lamp of an extinguishing member, means for actuating said extinguishing member to extinguish the flame of the heater, a weight for holding said extinguishing member normally in inoperative position against the action of said actuating means, and a 110 pocket member comprising a strip of sheet metal having its ends adapted to be secured to said extinguishing member and its intermediate portion offset from said extinguishing member to receive said weight in the 120 space between said offset portion and said extinguishing member.

9. The combination with a liquid fuel 115 heater or lamp of an extinguishing member, means for actuating said extinguishing member to extinguish the flame of the heater, a weight for holding said extinguishing member normally in inoperative position against the action of said actuating means, and a 125 pocket member comprising a strip of sheet 130

metal having its ends adapted to be secured to said extinguishing member and its intermediate portion offset from said extinguishing member to receive said weight in the space between said offset portion and said extinguishing member, the said offset portion being formed with an inwardly extending projection to be loosely engaged by said weight to hold the same in said pocket so that the weight will be displaced from said pocket when the heater is tipped over.

10. The combination with a liquid fuel heater or lamp of an extinguishing member, means for actuating said extinguishing member to extinguish the flame of the heater, a weight member having a beveled edge for holding said extinguishing member normally in operative position against the action of said actuating means, and a pocket member comprising a strip of sheet metal having its ends adapted to be secured to said extinguishing member and its intermediate portion offset from said ends to form a space between said intermediate portion and said extinguishing member to loosely receive said weight, said intermediate portion being formed with an inward projection to engage said beveled side of the weight member, whereby the said beveled side of the weight tends to force said pocket member away from said extinguishing member.

11. The combination with a liquid fuel heater or lamp of an extinguishing member, means for actuating said extinguishing member to extinguish the flame of the heater, a weight member for holding said extinguishing member normally in inoperative position against the action of said actuating means, and a pocket member comprising a strip of sheet metal having its ends returned at an angle and soldered at their edges by a fusible solder to said extinguishing member, the lower portion of said edges being inclined away from said extinguishing member so as to deflect said pocket member outwardly when said fusible solder melts and the pocket member falls.

12. The combination with a liquid fuel heater or lamp, of an extinguishing member, means for actuating said extinguishing member to extinguish the flame of the heater, a weight for holding said extinguishing member normally in inoperative position against the action of said actuating means, and a pocket member comprising a strip of sheet metal having its ends secured by a fusible element to said extinguishing member and its intermediate portion offset from said extinguishing member to receive said weight in the space between said offset portion and said extinguishing member.

WILLIAM K. BASSFORD.
